HATCH FRAME

Louis C. Wilkoff, Youngstown, Ohio, assignor, by mesne assignments, to Youngstown Steel Car Corporation, a corporation of Ohio

Original application February 7, 1936, Serial No. 62,856. Divided and this application March 1, 1937, Serial No. 128,551

11 Claims. (Cl. 108—5)

The present invention relates to hatch frames, for example, the frame surrounding the hatch opening of a refrigerator car, and aims generally to improve and simplify the construction of such frames as well as the construction of the car roof.

In the construction of refrigerator cars, there usually is provided at one or both ends of the car ice compartments for containing and storing the ice. The ice is introduced into the compartment through a hatch opening in the roof, which opening is adapted to be sealed by a hatch plug.

Modern refrigerator cars are equipped with metal roof sheets and the hatch frames are usually bolted or riveted to the roof sheet. In both cases the roof is subject to leakage around the bolts or rivets, thus shortening the life of the car roof structure.

Furthermore the hatch frame must preferably be made of metal of sufficient thickness and rigidity, as for example, from $\frac{1}{8}$ to $\frac{1}{4}$ inch steel plates, to adequately withstand the shock and wear on the wood framing of the car roof, when large cakes of ice are dumped through the hatch opening. The inner wall of the hatch frame must be relatively smooth, and preferably is of one-piece construction so as to smoothly and accurately fit the sealing hatch plug.

According to my invention I provide improved constructions of hatch frames and car roofs embodying hatch frames presenting a strong, stiff and rigid frame, preferably having a smooth one-piece well, and which may be securely attached and sealed to the roof sheets without requiring bolts, rivets or other types of fastenings, perforating the roof sheets. According to certain embodiments of the invention, the hatch frame may be secured in place and sealed to the roof sheets after the roof sheets have been applied to the car roof.

The subject matter of the present application is a division of my prior application, Serial Number 62,856, filed February 7, 1936.

These and other important aims and objects of the invention will be apparent from the following description, when considered with the accompanying drawing illustrating certain preferred embodiments of the invention.

In the drawing

Fig. 1 is a sectional view of a portion of a car roof and hatch frame constructed in accordance with one embodiment of the invention;

Fig. 2 is a plan view of the hatch frame;

Fig. 3 is a transverse sectional view of the hatch frame illustrated in Figs. 1 and 2;

Fig. 3a is a detail view illustrating a modified manner of clamping the hatch frame in place in the car roof.

Referring more particularly to the drawing, modern refrigerator cars include a sheathing roof 10, metal roof sheet 11, ceiling 12, certain structural framework 13 between the sheathing and ceiling, and a hatch opening 14 adapted to receive a hatch frame 15 and to be closed by a suitable hatch plug 16. The framework 13 may be of a variety of forms and construction, and usually includes some kind of box-like frame around the hatch openings and the space between the ceiling and roof sheathing is usually filled with suitable insulating material.

According to the form of my invention illustrated therein, I provide a hatch frame including a well 17, combing 18 and deck flange 19, of heavy metal, preferably wrought iron plate, from $\frac{1}{8}$ to $\frac{1}{4}$ inch wide in thickness, which frame may advantageously be made as by pressing from a single piece metal, to provide smooth, continuous, downwardly converging side and end walls, 20 and 21 respectively. By pressing the well 17 and at least a portion of the combing 18 from a single piece of metal, smooth side walls and uniform fillets are presented that will accurately receive and fit the hatch plug shown in dotted lines in Fig. 1.

The hatch frame thus constructed may be secured in position in the car, in a number of different ways according to the invention.

In the forms of invention illustrated in Figs. 1 and 3a, the frame is securely held in place by applying a downward clamping pressure to the frame at some point or points spaced from and preferably located below the roof sheet. According to these forms of invention, a suitable waterproof joint is provided between the deck flange 19 of the frame and the metal roof sheet 11, which may comprise a strip of bitumen coated fabric 22 such as canvas, and a layer of suitable plastic deck cement 23.

According to the form of invention shown in Fig. 1, a downwardly and outwardly flaring apron or skirt 24 may be attached to the lower edge of the well, as by welding along the edge as indicated at 24a, the lower edge of the skirt having an outwardly extending horizontal flange 25 adapted to underlie the ceiling 12. Suitable clamping means, as for example, wedge-shaped pieces 26, or clamping screws 27 (Fig. 3a), may be driven between the ceiling 12 and flange 25 to hold the hatch frame securely in place with the

deck flange 19 pressed tightly against the roof sheet 11.

5 In the embodiments of the invention thus described, it will be apparent that the hatch frame 15 may be secured in position after the roof sheet 11 has been applied to the car, which is a distinct advantage and economy over the prior practice of riveting the frame to the roof sheet on the ground and then putting the roof sheet 10 and frame in place on the car. Furthermore, the framework 13 need not be specially constructed to fit the hatch frame 15, and considerable space is provided between the framework 13 and hatch frame 15 that may be filled with 15 insulation, or if unfilled, will provide a dead air insulating space. The construction has many advantages in the economy of constructing the refrigerator car.

20 Advantages of the invention reside in the simplicity of construction of the hatch frame as well as of the car roof structure surrounding the hatch frame, as well as the improved watertight connection between the hatch frame and the metal roof sheet of the car. By reason of the 25 construction, the car roof frame is not subjected to shock and wear as in the case of many prior installations and need not be made to accurately accommodate the hatch plug.

30 The elimination of all vertical rivets or bolt connections between the hatch frame and car roof sheet also improves the watertightness of the roof as a whole, which is highly desirable in prolonging the life of the car roof structure.

35 Obviously, my invention is not to be restricted to the details described or as shown in the accompanying drawing which is intended as illustrative only.

I claim:

40 1. In a railway car construction, a metal roof sheet, a ceiling spaced therefrom, an opening in said ceiling and roof sheet, frame members interposed between said roof sheet and ceiling and adjacent said openings, a hatch frame positioned in said opening and provided with a combing overlying a portion of the roof surrounding the 45 opening therein, means for securing said hatch frame to said roof sheet to provide a waterproof joint therebetween, and means for applying a clamping pressure between said hatch frame and car structure to hold the hatch frame tightly against the roof sheet, said last named means including means formed as a unitary part of the hatch frame and having a portion underlying said ceiling.

50 2. In a refrigerator car construction, a metal roof sheet, a ceiling spaced therefrom, an opening in said ceiling and roof sheet, frame members interposed between said roof sheet and ceiling and adjacent said openings, a hatch frame positioned in said openings and provided with a combing overlying a portion of the roof surrounding the opening therein, means for securing said hatch frame to said roof sheet to provide an imperforate waterproof joint therebetween, 55 and means for applying a clamping pressure between said hatch frame and car structure to hold the hatch frame tightly against the roof sheet, said last named means being formed as a unitary part of the hatch frame well and including an outwardly flaring skirt, and clamping means between said skirt and car ceiling.

60 3. In combination with a refrigerator car having a roof and a ceiling spaced below said roof, of a hatch frame positioned in said roof, said frame having a portion bearing on the upper sur-

face of the roof and another portion extending below said ceiling, and means for applying a clamping pressure between the lower portion of the hatch frame and ceiling to press the bearing portion of said frame tightly against the roof 5 to provide a watertight joint therebetween.

4. In combination with a refrigerator car having a ceiling and a roof, of a hatch frame positioned within the roof and having a portion bearing on the upper surface thereof, an apron connected to the frame and extending below the ceiling and means interposed between the apron and ceiling for exerting a downward clamping pressure on said hatch frame.

5. In combination with a refrigerator car having a ceiling and a roof, of a hatch frame positioned within the roof and having a portion bearing on the upper surface thereof, an apron rigidly connected to the frame and extending below the ceiling and means interposed between 20 the apron and ceiling for exerting a downward clamping pressure on said hatch frame.

6. In combination with a refrigerator car having a ceiling and a roof, of a hatch frame positioned within the roof and having a portion bearing on the upper surface thereof, an apron connected to the frame and extending below the ceiling and wedge-shaped means interposed between the apron and ceiling for exerting a downward 25 clamping pressure on said hatch frame.

7. In combination with a refrigerator car having a ceiling and a roof, of a hatch frame positioned within the roof and having a portion bearing on the upper surface thereof, an apron connected to the frame and extending below the 30 ceiling and threaded means interposed between the apron and ceiling for exerting a downward clamping pressure on said hatch frame.

8. In combination with a refrigerator car having a ceiling and a roof, of a hatch frame positioned within the roof and having a portion bearing on the upper surface thereof, an apron connected to the frame and extending below and underlying the ceiling and means interposed between the apron and ceiling for exerting a downward 40 clamping pressure on said hatch frame.

9. A hatch frame for roofs of refrigerator cars and the like having a roof and a ceiling spaced below the same, said frame comprising a metal 50 well formed with downwardly and inwardly sloping side and end walls, a supplemental frame rigidly secured to said first-named frame and having certain of its walls downwardly and outwardly sloping, a laterally extending flange on the supplemental frame underlying the ceiling of the car, and means positioned between said flange and ceiling for exerting a downward clamping pressure on said hatch frame.

10. A hatch frame for roofs of refrigerator cars and the like having a roof and a ceiling spaced below the same, said frame comprising a metal 60 well formed with downwardly and inwardly sloping side and end walls, a supplemental frame rigidly secured to said first-named frame and having certain of its walls downwardly and outwardly sloping, a laterally extending flange on the supplemental frame underlying the ceiling of the car, and wedge-shaped means positioned between said flange and ceiling for exerting a downward clamping pressure on said hatch frame.

11. A hatch frame for roofs of refrigerator cars and the like having a roof and a ceiling 70

spaced below the same, said frame comprising a metal well formed with downwardly and inwardly sloping side and end walls, a supplemental frame rigidly secured to said first-named frame and having certain of its walls downwardly and outwardly sloping, a laterally ex-

tending flange on the supplemental frame underlying the ceiling of the car, and threaded means positioned between said flange and ceiling for exerting a downward clamping pressure on said hatch frame.
